DISPLAY COVER

Jacob I. Russakov, Chicago, Ill.

Application July 17, 1933, Serial No. 680,779

6 Claims. (Cl. 220—32)

These improvements relate to readily applicable and removable covers for use upon the open tops of relatively long and narrow boxes so as to display, while protectively enclosing, their contents. My Patent No. 1,540,807 of June 9, 1925 shows a display cover of the present type, and sets forth the prime objects and advantages of such a device. The more specific objects of these improvements are to provide peculiarly advantageous means for holding the lids for swinging movements, and for holding a pane of glass in a lid of such kind. Also the provision of thin lids, but slightly thicker than the glass used as the transparent element of them, lids which are peculiarly strong, occupy less than the usual amount of space, and which, taken with recessed seats for them, provide a cover substantially flat over its entire top surface. In this connection also it is an object to provide a display cover having lids of such construction and so arranged that they may be hinged close to each other at the middle of the device to such effect that either of the two lids may be laid over immediately above the other lid, whereby full access may be had to the contents of the box at each end as well as in the middle, and with the open lid in an out-of-the-way position, and not upstanding outwardly and away from the plane of the device as a whole at a substantially large angle. It is an object also to provide a construction according to which the several parts may be assembled readily and conveniently, with a saving of time and labor. Still other objects and advantages will appear hereinafter.

In the accompanying drawing Figure 1 is a perspective view of my improved display cover, with a box, over the open top of which it telescopically fits, fragmentarily shown;

Fig. 2 is a bottom plan view of the cover device of Fig. 1 interiorly broken away;

Fig. 3 is an enlarged fragmentary sectional view as on the line 3—3 of Fig. 1;

Fig. 4 is a fragmentary sectional view as on any of the lines 4—4 of Fig. 1;

Figs. 5 and 7 are perspective views showing details of two forms of hinge-pin-holding means;

Fig. 6 is a bottom view of the preferred form of the hinge-pin units, following the fragmentary construction of Fig. 7;

Fig. 8 is a vertical transverse sectional view through either one of the opposed side frame members at the middle thereof, showing the application of the hinge-pin unit of either Fig. 5 or Fig. 7; and

Fig. 9 is a horizontal sectional view through

the lower left-hand corner of Fig. 1 showing the seam construction at each of the four corners of the body frame.

The body of the device is a rectangular frame formed from thin sheet metal such as tin and comprises a pair of opposed side members having depending flange-like strips 15 (Figs. 1 and 8) and a narrow strip-like part 16 turned over at right angles from flange 15, the inner edge portions of the material (Fig. 8) being bent downward at right angles a short distance at 17, then bent inward horizontally at right angles at 18, with the extreme inner edge portion turned back upon itself at 19 to form a bead where the hand of the user passes through the opening defined by the seat portion 18 and its bead 19.

The end walls have side flanges 20 like side flanges 15, the flat top surface part 21 like part 16, and the part 21 is bent downward the same as at 17 (Fig. 8) and has also a seat part the same as 18 and the bead 19. In other words, the sectional view of Fig. 8, as to the parts 15, 16, 17, 18 and 19, illustrates also the construction of the end members of the frame.

Fig. 9 shows how the side and end members are joined at the corners, namely by the interfolding of the vertical edge portions providing a seam marked 22. This seam is to be understood to be the same at the four corners.

The body frame thus produced has a flat horizontal rectangular narrow top surface, about an inch in width, in my practice, marked 16 and 21 in Fig. 1, with depending flanges, about an inch and a quarter in their vertical directions in my practice, marked 15 and 20 in Fig. 1, with a single large open interior defined by the seat 18 and its bead 19 at the sides and at the ends as shown for the sides in Fig. 8.

Turning to Figs. 6 and 7, showing the preferred form of hinge-pins and holding means therefor there is first a right-angular sheet-metal cleat 25 having a leaf 26 provided with a rivet hole 27 and a leaf 28 having a pair of seats 29 and 30 pressed therein parallel to each other and being adapted to receive the straight iron rods or wire sections 31 and 32 respectively, these rods being rigidly secured, as by welding, to the part 28 in said seats. Fig. 6 shows two of the constructions of Fig. 7 with the free ends of the rods 31 and 32 shown substantially end to end as to those in alignment with each other, their middle portions being broken away. The same reference characters are given to the corresponding wires of each unit. These two units are alike and one is simply turned around for application to the

other side. Fig. 2 shows how they are held, with a rivet marked 27a passing through the hole 27 of Fig. 7, and holding the cleat part 26 against the flange part 15 of the body, with the part 28 of the cleat tightly against the top part 16 of the frame. The part 28 is preferably of such length that it fits snugly between the parallel frame parts 15 and 17 (Fig. 8). Since the wires 31 and 32 are rigidly secured to the cleat part 28, as by welding, these wires are held strongly and provide unusually satisfactory hinge-pins for the swinging lids. The two rods 31 and 32 are so close together that when the tubular parts marked 34 and 35 of the lids in Figs. 1 and 3 are around these wires respectively these tubular parts 34 and 35 are so substantially close to each other side by side as effectively to close the top at the hinges whereby no further protection for the contents at that place is necessary.

20 A modified form of hinge-pin unit is shown in Fig. 5 where the parallel hinge-pins 37 and 38 are short, for example one or two inches in length. They are shown as of one piece of wire bent U-shape and are held as by welding in the U-shaped seat marked 39 pressed into the part 40 of the retaining cleat having the part 41 and a rivet hole 42. The illustration of Fig. 8 serves also to illustrate the application of the unit of Fig. 5.

30 Turning next to the two swinging lids, these are alike and comprise a narrow rectangular frame of sheet metal such as tin. From Fig. 4 it is seen that the upper strip-like part 50 has an inner annular embossment 51 and an outer annular embossment 52, the latter being at the elevation of the part 16 of the body frame. The lid frame turns at 53 to form space for the glass pane 54 and then turns inward to provide the integral strip-like part 55. This construction shown in Fig. 4 is the same along three edges of the glass (omitting the inner edge) and I have applied section lines 4—4 at several places in Fig. 1 to indicate this fact. A metal binding is thus provided around three edges of the glass pane.

45 Fig. 3 shows the construction along the inner edges of the two lid frames. There the upper strip-like part marked 50a, and which corresponds to the part marked 50 in Fig. 4, has the bead 52 modified to provide the tubes 34 and 35 (Figs. 1 and 4) within which are the four hinge rods 31 and 32 shown in Fig. 6. The use of the metal for the hinge formation at 34 and 35 leaves open at 57 and 58 (Fig. 3) the channel shown between parts 50 and 55 in Fig. 4, that channel extending on three sides of the lid frame, but being open at the inner side thereof. The glass may therefore simply be inserted into that channel as one puts a card into an envelope, and the pane is there held securely on three sides. To hold the pane securely I provide a short extension of the lower lid frame parts 55 slightly beyond the glass adjacent to the hinge, and to hold the glass readily removably it is merely necessary to bend toward the glass the free corner of that extension marked 60 in Fig. 3. Should a pane become broken a new one can readily be inserted by merely bending outward that bent-in corner 60.

70 Many suggestions heretofore have been made of wire and other spring devices for holding the glass member of display cover lids for ready removability. The lids in such cases are relatively quite thick and usually require considerable thickness to accommodate such holding

means. By the present construction I provide a means for retaining the glass which at once reinforces the glass with the binding strip around the three of its edges where such binding is peculiarly advantageous, provide a binding which is rounded and smooth to the touch, provide a lid which is only slightly thicker than the pane of glass used, and, together with the recessed seat for it in the main frame, provide a construction for the device as a whole that is free of parts upstanding from the top surface of the frame except for the finger-buttons marked 63 in Fig. 1, and by these means too I introduce an ornamental effect that is of commercial value.

80 To provide a construction of this kind and character involved numerous problems among which was that of the assembly of the device in manufacture. Turning to Fig. 8 it will be noted that an opening marked 65 is made in the short vertical wall 17 to accommodate the pair of rods 31 and 32. The dotted lines in that figure show the first step in the application of the hinge-pin unit to the side frame member, this unit simply being slipped into place, and it is then riveted in its final position. The body side frame members at this time, however, have not yet been assembled with the end frame members, but remain separate pieces. Having secured the two hinge-pin units to the side frames according to Fig. 8, the lids are next assembled 95 upon the hinge-pins, and the side frames thus become assembled with the lids in their final position as shown in Fig. 1. The next step is to bring the end frames of the body into association with the side frames, and the end and side frames 100 are then seamed together at the corners at the 105 seams marked 22 in Figs. 1, 2 and 9. I prefer also to rivet the overlapping lid rests 18 by rivets marked 66 in Fig. 2.

110 I contemplate as being included in these improvements all such variations, changes and departures from what is thus specifically illustrated and described herein as fall within the 115 scope of the appended claims.

I claim:

120 1. In a display cover adapted to fit upon the open end of a box and comprising a substantially rectangular interiorly-open frame having opposed frame members, the combination therewith of means for securing a lid to said frame comprising a pair of spaced-apart metallic cleats secured to the frame and a rod permanently and substantially rigidly secured to each cleat, said rods being directed toward each other in aligned 125 relation, and a lid adapted to rest upon the frame 130 when in closed position and having substantially tubular means encompassing said rods and extending substantially continuously between the cleats.

135 2. In a display cover of the character described comprising a substantially rectangular frame having opposed side members and opposed end members defining an open interior, the combination therewith of a pair of lids covering said open interior, and means for hinging the lids comprising 140 two pairs of parallel rods extending inwardly from and being permanently and substantially rigidly secured to the side members respectively of the frame, the rods of each pair being in aligned 145 relation, the lids having substantially tubular elements at their inner edge portions encompassing aligned rods of said pairs respectively, the said lids including the said tubular elements extending substantially continuously between the side members of the frame and being in close side by side 150

relation substantially filling the space between each other and the side members.

3. In a display cover of the character described comprising a rectangular frame having opposed side members and opposed end members, the combination therewith of a pair of metallic cleats secured to the side frame members respectively, each cleat being formed with seat means adapted to accommodate one each of a pair of rods to extend therefrom in parallel relation to each other, one each of a pair of parallel rods substantially close together rigidly secured to each cleat in the seat means therefor, the rods held by one cleat being directed respectively toward the rods held by the other cleat so that the rods of a pair are in end to end aligned relation, and a pair of lids each having a frame formed of thin sheet metal, the inner edge portions of each lid being formed tubularly, said tubular formations encompassing the rods of a pair respectively and being thereby adapted to swing on said rods into open and closed position, the said lids including the said tubular formations extending substantially continuously between the said members of the frame and being in close side by side relation substantially filling the space between each other and the side members.

4. A hinge unit for a display cover of the character described comprising a sheet metal cleat having leaves bent substantially at right angles to each other, one leaf being formed with depressions providing seats to receive a pair of wires to extend therefrom substantially parallel to each other, a pair of substantially rigid wires received in said seats respectively, and a frame member cooperating with the cleat to retain the wires in said cleats.

5. In a display cover adapted to fit upon the open end of a box, the combination comprising a substantially rectangular interiorly open sheet metal frame having opposed side members each including an upper portion and a depressed seat, a pair of spaced-apart metallic cleats secured to the side members medially thereof, each cleat being carried by one of the opposed side members upon the under side of said upper portion, two closely adjacent parallel rods permanently and substantially rigidly secured between each cleat and its respective side member, said rods being directed toward each other to provide two pairs of oppositely directed aligned rods lying between said upper portions of the side members and said depressed seats whereby the rods are wholly enclosed at each end by the frame, and a pair of lids adapted to rest upon said seats when in closed position, each lid having a substantially tubular portion encompassing the aligned rods of a pair, said tubular portions being in contacting side-by-side relationship and extending substantially continuously between said upper portions of the side members whereby the said lids including said tubular portions substantially fill the space between each other and the upper portions of the frame members and are substantially flush therewith.

6. The structure of claim 5 wherein the cleats have depressions therein to receive the rods and wherein the pair of rods carried by each cleat are formed integrally and the depression in the cleat is in the form of a U receiving the bight of the integral pair.
